Primary Examiner — Ian Simmons*Assistant Examiner* — Richelle G Shelton(74) *Attorney, Agent, or Firm* — Erickson Kernell Derusseau & Kleypas, LLC(57) **CLAIM**

The ornamental design for a display screen with graphical user interface for an electrotherapy device, as shown and described.

DESCRIPTION

FIG. 1 is a front view of a display screen with graphical user interface for an electrotherapy device; and,
 FIG. 2 is a front view of a second embodiment thereof.
 The broken line showing of the boundary of the graphical user interface forms no part of the claimed design.
